UNITED STATES PATENT OFFICE

JACOB V. DYRE, OF BELL, CALIFORNIA

SPRING HARROW TOOTH

Application filed December 26, 1928. Serial No. 328,513.

In the present state of the art, spring tooth harrows are commonly provided with tooth carrying shanks made of flat spring steel straps, that are mainly straight in transverse section and are longitudinally curved to an appropriate form and that are adapted at the upper end to be detachably fastened to a cross bar of a harrow frame, and to stand forwardly and downwardly aslant at the lower end, and that are adapted to carry a forwardly extending detachable tooth that is fixed to the lower end of the shank by one or more bolts passed through bolt holes in the shank and the tooth, and secured by nuts.

Such detachable harrow teeth are commonly double pointed longitudinally arcuate transversely V-shape steel drop forgings having an arcuate longitudinal middle ridge in front and a groove complementary thereto at the rear, and it is known to the prior art that the tooth, and the lower end of the shank, may be fitted together spoon fashion and fastened together by a single bolt.

Various difficulties arise in the use of harrows of this type as heretofore known, among which may be mentioned the clogging of the teeth and shank with weeds, grass and other débris, and the setting up of a vibrating action of the shanks and teeth.

An object of this invention is to avoid such difficulties and furthermore to provide means whereby points of various widths may be used on the spring teeth, and the teeth will be firmly held and may be reversed with comparative ease and convenience with minimum loss of time.

This invention comprises a novel construction of spring tooth shank, and a novel assembly of parts that are combined to accomplish the foregoing objects.

The novel spring tooth shank I have invented is provided at its lower or free end with an elongated recess having at its front a longitudinal anteriorly concave arcuate ridge adapted to be fitted upon by the rear face of a harrow tooth point of the usual, and also of a changed form, and is provided on its rear face with a groove complementary to the front face, and is provided centrally with a bolt hole to accommodate a rearward-

ly projecting burr from the tooth point, and a plow mold-board bolt inserted from front to rear and secured by a nut accommodated by the groove in the rear face of the seat.

The rear face of the forward end of the harrow tooth is pointed and bevelled to an edge adapted to fit against the rear face of the harrow tooth point.

A feature of the newly invented spring tooth is that the curved main body of flat spring steel, terminates at its lower or free end in an arcuate portion, the edges of which are rearwardly bent to form a groove fitted to the grooved rear side of the harrow tooth point.

An advantage of the construction of the burr and its seat is that the point can be immovably fixed to the spring tooth by a single bolt. Another advantage of the invention is that the liability of clogging is minimized in that the spring tooth is provided with a rearward kink or deflection just above the upper end of the harrow tooth so that as accumulations of trash are forced up over the top of the upper end of the tooth point, the same will be loosened from packed position and will fall from the tooth. This shedding of the accumulations is facilitated by the bevel of the front of the tooth end to which bevel the forward face of the kink is tangent.

The novel form of the tooth and tooth point at the bolt holes therein also insure a tight firm fit.

Other objects, advantages and features of invention may appear from the accompanying drawings, the subjoined detailed description and the appended claims.

The accompanying drawings illustrate the invention.

Figure 1 is a side view of the harrow spring tooth with point attached and fixed in position on the cross bar of a harrow frame.

Fig. 2 is a rear view of what is shown in Fig. 1.

Fig. 3 is a fragmental front view of what is shown in Fig. 1, the fragment of the harrow frame being omitted and the attaching end of the spring tooth being broken away.

Fig. 4 is a view analogous to Fig. 3 show-

ing the appearance when the tooth is supplied with a narrow point.

Fig. 5 is a fragmental axial section of the spring tooth and point on line indicated at 5 x5, Figs. 2 and 3.

Fig. 6 is a cross section on line x6, Fig. 5.

Fig. 7 is a cross section on line x7, Fig. 5.

Fig. 8 is a cross section on line x8, Fig. 5.

Fig. 9 is a side elevation of the portion 10 of the spring tooth shown in Fig. 5.

Fig. 10 is a perspective front view of the portion of the spring tooth shown in Fig. 5 and also indicates, detached therefrom, a front view of the point shown in said Fig. 5.

Fig. 11 is a perspective fragmental rear view of the portion of the spring tooth shown in Figs. 5, 9 and 10.

Arrows on the section lines in the several views indicate the direction of sight on the 20 respective sections.

The spring tooth 1 is of conventional form except at its lower or free end where it is provided with a seat 2 having at its front a longitudinal anteriorly concave arcuate ridge 25 3 adapted to be fitted upon by the rear face 4 of a harrow tooth point 5. The point seat is provided with a bolt hole 6 through the ridge and is provided on the rear side with a channel 7 adapted to accommodate a nut 8 30 and a counter-sunk bolt 9 in the counter-sunk bolt hole 10 of the point and the bolt hole 6 of the tooth. The under rear side of the spring tooth is bevelled or chamfered as at 11 at the end of the spring tooth.

35 By this novel construction and arrangement the spring tooth may be fitted with any of the standard harrow teeth points now on the market in various widths as indicated in Figs. 3 and 4.

40 In Fig. 3 the point 5 is of the same width as the spring tooth while in Fig. 4 the point 5 is narrower, and in such narrower form the cutting edge 12 of the tooth serves to cut the ground, the roots and the surface weeds

45 with which the edge 12 of the spring tooth contacts and in any instance such cutting edge does not afford an abutment against which the weeds and débris will become clogged, and the tool passes through the soil 50 more freely than has heretofore been possible with the teeth of spring tooth harrows.

The kink or rearward deflection 13 of the spring tooth above the tooth point seat 2 is provided to abruptly release the pressure 55 from below upon the tooth clogging accumulations forced up the tooth as the tooth advances, thus allowing the weeds, grass and trash to shake loose and drop to the ground behind the tooth.

60 In drop forging the tooth point I form a front countersink 14 to receive the bolt head, and a rearwardly projecting marginal burr 15, formed by the operation of punching the countersunk hole 10; and I provide the front 65 of the seat 2 with a countersink 16 at the bolt

hole, adapted to accommodate the projection 15, thus to increase the security of the attachment of tooth point to the tooth when the bolt is inserted and the nut screwed home. The rear face 17 of the tooth at the hole 10 is 70 flattened so that the nut will fit snugly thereon when screwed home.

I claim:

1. A harrow spring tooth having a tooth point seat provided with a countersunk bolt-hole; a tooth point having a bolt-hole countersunk at the front and a projection at the back to engage the countersink in the point seat; a bolt in the bolt-holes and a nut on the bolt adapted to hold the bolt head seated in 80 the countersink of the tooth point.

2. In combination, a spring harrow tooth shank having a longitudinal arcuate anteriorly concave tooth holding recess, and that is of an anteriorly convex V shape in 85 cross-section; said shank being provided with an anteriorly countersunk bolt hole; the posterior face of said recess forming a seat adapted to chamber a nut for a tooth holding bolt in said bolt hole, a harrow tooth provided with an anteriorly countersunk bolt hole and with a posterior burr at the margin of said bolt hole to fit in the countersink of the shank, the portion of said tooth above said bolt hole being accommodated in the recess 95 of the shank and said burr being accommodated in the countersink of the hole in the shank, a bolt in said holes and a nut accommodated in the concavity of the shank securing the bolt in said bolt hole and holding said 100 burr seated in the countersink in the shank.

3. The combination with a harrow tooth having a bolt hole, of a spring shank having a kink and having a bolt hole between the kink and the lower end of the shank, and also having below the kink a seat that accommodates the portion of the tooth that is above the bolt hole so that the lower end of the kink forms a smooth upward and rearward continuation of the forward face of the 110 upper end of the tooth thus to allow compacted accumulation of growth to loosen and be shunted off of the shank.

4. In a harrow, the combination with a tooth having a longitudinally concave and transversely convex front and having front bevel faces at both ends and a bolt hole between such faces; of a spring shank having a bolt hole to register with the bolt hole of the tooth, and a recess extending above the 120 bolt hole to accommodate the portion of the tooth above the bolt holes and having a kink above the recess, the forward face of the kink being tangent to the front of the tooth so that accumulations forced up in front of the tooth 125 during the harrowing operation will become loosened and will slide from the tooth and fall off of the shank.

5. The combination with a harrow tooth, of a spring shank to which the tooth is fixed; 130

said shank having a kink, and also having below the kink a seat that accommodates the upper portion of the harrow tooth so that the lower end of the kink forms a smooth upward and rearward continuation of the forward face of the upper end of the tooth, thus to allow compacted accumulations of growth to loosen and be shunted off of the shank.

6. In a harrow, the combination with a tooth having front bevel faces at both ends; of a spring shank, to the front face of which the tooth is attached, said shank having a kink, the forward face of which is tangent to the front of the tooth so that accumulations forced up off of the front of the tooth during the harrowing operation will become loosened and slide off of the shank.

In testimony whereof, I have hereunto set my hand at Los Angeles, California, this 26th day of October, 1928.

JACOB V. DYRR.
